(57) **CLAIM**

The ornamental design for a scanner for an X-ray tomography diagnosis apparatus, as shown and described.

DESCRIPTION

FIG. 1 is a front, top and right side perspective view of a scanner for an X-ray tomography diagnosis apparatus, showing my new design;

FIG. 2 is a top, rear and right side perspective view thereof;

FIG. 3 is a front view thereof;

FIG. 4 is a right side view thereof, the opposite side being symmetrical;

FIG. 5 is a top view thereof;

FIG. 6 is a rear view thereof;

FIG. 7 is a bottom view thereof;

FIG. 8 is a cross sectional view thereof taken along line 8-8 in FIG. 3;

FIG. 9 is a cross sectional view thereof taken along line 9-9 in FIG. 3;

FIG. 10 is an enlarged fragmented view thereof taken along line 10 in FIG. 8;

FIG. 11 is an enlarged fragmented view thereof taken along line 11 in FIG. 8;

FIG. 12 is an enlarged fragmented view thereof taken along line 12 in FIG. 9; and,

FIG. 13 is a front, top and right side perspective view thereof with the body sloped backward.

The broken lines in FIGS. 8 and 9 are included to indicate the point at which the magnified view is cut off. The broken lines are for illustrative purposes only and form no part of the claimed design.
